MUZZLE RECOIL CHECK FOR GUNS

Nicolas Emilian Methlin, Paris, France, assignor
to Schneider & Cie., Paris, France, a company
of France

Application November 29, 1935, Serial No. 52,265
In France December 7, 1934

10 Claims. (Cl. 89—14)

The present invention relates to a device for reducing the length of recoil of guns, namely a device of the type known as "muzzle recoil check".

5 There exist devices of this kind which comprise exclusively lateral discharge orifices, that is to say, orifices whereof the axial plane coincides with the horizontal axial plane of the gun barrel. Similar muzzle recoil checks have already been proposed wherein the said lateral orifices are formed partly in a discharge nozzle fitted on the muzzle of the gun and partly in a terminal tubular member mounted on the nozzle.

10 This invention relates to improvements in the muzzle recoil checks constituted in this way, and it is characterized by special forms of and methods of assembling the two principal elements (the nozzle and the tubular element), ensuring together an economical and practical construction and machining and at the same time considerable facility in the operations of assembling and dismounting as well as convenient replacement of worn parts.

15 According to the invention, the flared nozzle is flattened so that above and below it is bounded by plane walls wherein, however, are provided recesses for ensuring the connection between the muzzle of the gun barrel and the tubular outlet element. Furthermore, the terminal tubular element and the complementary elements of the escape orifices carried by the said tubular element are formed in a member which is fitted into the nozzle simply by tongue and groove attachment and which may thus be slid into position. The sliding member carrying the tubular element is retained on the nozzle in a very simple manner by means of an internally screw-threaded ring screwed on an external thread on the nozzle and slid over the tubular element.

20 A practical form of construction of the invention is shown by way of example in the accompanying drawing, wherein:—

25 Figure 1 is a longitudinal sectional elevation showing the elements of the muzzle recoil check assembled together, the nozzle being screwed on the end of the muzzle of the gun barrel.

30 Figure 2 is a sectional plan on the line II—II in Figure 1 with a portion shown in full, the muzzle recoil check being shown separate from the gun barrel.

35 Figure 3 is a cross-sectional elevation on the line III—III in Figure 2.

40 Figure 4 is a section on the line IV—IV in Figure 1.

45 In these various figures, *a* denotes the part

5 of the muzzle recoil check which forms the nozzle and which by its internally screwthreaded cylindrical rear portion *a*¹ is screwed on the muzzle *b* of the gun barrel, as shown in Figure 1. As shown by the cross-sections in Figure 3, the body of the nozzle has the form of a flattened funnel, the internal wall comprising plane surfaces *a*² and *a*³ above and below. Formed on the front end of the funnel are the rear portions *a*⁴ of the lateral discharge orifices, the complementary portions of the latter being formed, as will be seen hereinafter, in the tubular element of the recoil check. Projecting from the body *a* of the nozzle are lateral pieces *a*⁵ of a length equal to the width of the mouth and provided with grooves 10 *a*⁶ for engagement by corresponding tongues carried by the complementary element constituting the tubular element. Formed on the side pieces *a*⁵ are lugs *a*⁷ whereof the plane internal faces 15 form guiding and retaining means for the body 20 of the tubular element, while the cylindrical external surface is screwthreaded to receive an internally screwthreaded ring for assembling together the nozzle and the tubular element.

25 The tubular discharge element *c* is formed as a sliding member in the rear portion whereof are provided the portions of the discharge orifices *c*¹ which, together with the elements *a*⁴ of the nozzle, complete the said orifices. The body of the sliding member *c* has projecting tongues *c*² above 30 and below of a profile corresponding to that of the grooves *a*⁶ in the nozzle.

35 The member carrying the tubular element, on which are formed the complementary portions *c*¹ of the discharge orifices, is mounted on the nozzle *a* as will be seen by the simple engagement of the tongues *c* with the grooves *a*⁶ in the front end portion of the nozzle.

40 For retaining the tubular element on the nozzle, there is provided an internally screwthreaded ring *d* which, as stated hereinbefore, is screwed on the threads provided on the lugs *a*⁷ of the nozzle, the ring comprising a portion of reduced diameter corresponding to the external diameter 45 of the tubular element and mounted on the latter simply by a sliding fit, as may be seen clearly in Figures 1 and 2. The assembly ring having thus been fitted and screwed on, it may be secured in position by a grub screw *e* such as shown 50 in Figure 1.

45 Of course, the assembly ring may comprise faces such as those indicated in dotted lines in Figure 4 in order to facilitate its manipulation, after the manner of an ordinary nut. 55

What is claimed is:—

1. A muzzle recoil check for gun barrels comprising a nozzle member adapted to be secured at its inner end to the muzzle of a gun barrel and having an axially extending, flaring passageway therethrough, a terminal member housed within the outer end of said nozzle member having a cylindrical passageway therethrough coaxial with said flaring passageway, means forming lateral discharge orifices connecting with said flaring passageway through which the projectile propelling gases may escape, the outer end of said nozzle member having diametrically opposite openings formed in the side walls thereof through which said terminal member is slidable into assembled position, and means for detachably connecting said nozzle and terminal members together in assembled relation including a tongue and groove connection therebetween extending at right angles to the axis of said passageways. 5
2. A muzzle recoil check for gun barrels comprising a nozzle member adapted to be secured at its inner end to the muzzle of a gun barrel and having an axially extending, flaring passageway therethrough, a terminal member housed within the outer end of said nozzle member having a cylindrical passageway therethrough coaxial with said flaring passageway, means forming lateral discharge orifices connecting with said flaring passageway through which the projectile propelling gases may escape, the outer end of said nozzle member having diametrically opposite openings formed in the side walls thereof through which said terminal member is slidable into assembled position, and means for detachably connecting said nozzle and terminal members together in assembled relation including a pair of grooves formed in the inner surface of said nozzle member adjacent the outer end thereof and extending laterally thereacross at right angles to the axis of said flaring passageway and a pair of complementary tongues carried by said terminal member and adapted for sliding engagement with said grooves. 10
3. A muzzle recoil check for gun barrels comprising a nozzle member adapted to be secured at its inner end to the muzzle of a gun barrel and having an axially extending, flaring passageway therethrough, a terminal member housed within the outer end of said nozzle member having a cylindrical passageway therethrough coaxial with said flaring passageway, means forming lateral discharge orifices connecting with said flaring passageway through which the projectile propelling gases may escape, the outer end of said nozzle member having diametrically opposite openings formed in the side walls thereof through which said terminal member is slidable into assembled position, and means for detachably connecting said nozzle and terminal members together in assembled relation including a pair of grooves formed in the inner surface of said nozzle member adjacent the outer end thereof and extending laterally thereacross at right angles to the axis of said flaring passageway and a pair of complementary tongues carried by said terminal member and adapted for sliding engagement with said grooves. 15
4. A muzzle recoil check for gun barrels comprising a nozzle member adapted to be secured at its inner end to the muzzle of a gun barrel and having an axially extending, flaring passageway therethrough, a terminal member housed within the outer end of said nozzle member having a cylindrical passageway therethrough coaxial with said flaring passageway, means forming lateral discharge orifices connecting with said flaring passageway through which the projectile propelling gases may escape, the outer end of said nozzle member having diametrically opposite openings formed in the side walls thereof through which said terminal member is slidable into assembled position, and means for detachably connecting said nozzle and terminal members together in assembled relation including a tongue and groove connection therebetween extending at right angles to the axis of said passageways, and means for locking said members against relative movement therebetween in the direction of said tongue and groove connection. 20
5. A muzzle recoil check for gun barrels comprising a nozzle member adapted to be secured at its inner end to the muzzle of a gun barrel and having an axially extending, flaring passageway therethrough, a terminal member housed within the outer end of said nozzle member having a cylindrical passageway therethrough coaxial with said flaring passageway, means forming lateral discharge orifices connecting with said flaring passageway through which the projectile propelling gases may escape, the outer end of said nozzle member having diametrically opposite openings formed in the side walls thereof through which said terminal member is slidable into assembled position, and means for detachably connecting said nozzle and terminal members together in assembled relation including a pair of grooves formed in the inner surface of said nozzle member adjacent the outer end thereof and extending laterally thereacross at right angles to the axis of said flaring passageway and a pair of complementary tongues carried by said terminal member and adapted for sliding engagement with said grooves. 25
6. A muzzle recoil check for gun barrels comprising a nozzle member adapted to be secured at its inner end to the muzzle of a gun barrel and having an axially extending, flaring passageway therethrough, a terminal member housed within the outer end of said nozzle member having a cylindrical passageway therethrough coaxial with said flaring passageway, means forming lateral discharge orifices connecting with said flaring passageway through which the projectile propelling gases may escape, the outer end of said nozzle member having diametrically opposite openings formed in the side walls thereof through which said terminal member is slidable into assembled position, and means for detachably connecting said nozzle and terminal members together in assembled relation including a pair of grooves formed in the inner surface of said nozzle member adjacent the outer end thereof and extending laterally thereacross at right angles to the axis of said flaring passageway and a pair of complementary tongues carried by said terminal member and adapted for sliding engagement with said grooves, and means for preventing relative movement between said tongues and grooves when said members are in assembled relation. 30
7. A muzzle recoil check for gun barrels comprising a nozzle member adapted to be secured at its inner end to the muzzle of a gun barrel and having an axially extending, flaring passageway therethrough, a terminal member housed within the outer end of said nozzle member having a cylindrical passageway therethrough coaxial with said flaring passageway, means forming lateral discharge orifices connecting with said flaring passageway through which the projectile propelling gases may escape, the outer end of said nozzle member having diametrically opposite openings formed in the side walls thereof through which said terminal member is slidable into assembled position, and means for detachably connecting said nozzle and terminal members together in assembled relation including a tongue and groove connection therebetween extending at right angles to the axis of said passageways, and means for locking said members against relative movement therebetween in the direction of said tongue and groove connection. 35
- 75

- openings formed in the side walls thereof through which said terminal member is slid able into assembled position, means for detachably connecting said nozzle and terminal members together 5 in assembled relation including a pair of grooves formed in the inner surface of said nozzle member adjacent the outer end thereof and extending laterally thereacross at right angles to the axis of said flaring passageway and a pair of complementary tongues carried by said terminal member and adapted for sliding engagement with said grooves, and means for preventing relative movement between said tongues and grooves when said members are in assembled relation including 10 a locking ring having a sliding fit with the exterior of said terminal member and a threaded connection with said nozzle member.
8. A muzzle recoil check for gun barrels comprising a flattened nozzle member adapted to be secured at its inner end to the muzzle of a gun barrel and having an axially extending, laterally flaring passageway therethrough, the upper and lower walls of said nozzle member being substantially flat and parallel to one another, a 15 terminal member housed within the outer end of said nozzle member having a cylindrical passageway therethrough coaxial with said flaring passageway and of substantially the same diameter as the height of said flaring passageway, means 20 forming lateral discharge orifices connecting with said flaring passageway through which the projectile propelling gases may escape, the outer end of said nozzle member having diametrically opposite openings formed in the side walls thereof 25 through which said terminal member is slid able into assembled relation, and means for detachably connecting said nozzle and terminal members together in assembled relation including a tongue and groove connection therebetween extending 30 at right angles to the axis of said passageways.
9. A muzzle recoil check for gun barrels comprising a flattened nozzle member adapted to be secured at its inner end to the muzzle of a gun barrel and having an axially extending, laterally flaring passageway therethrough, the upper and lower walls of said nozzle member being substantially flat and parallel to one another, a 35 terminal member housed within the outer end 40 of said nozzle member adjacent the outer end thereof and extending laterally thereacross at right angles to the axis of said flaring passageway, and a pair of complementary tongues carried by said terminal member and adapted for sliding engagement with said grooves.
- of said nozzle member having a cylindrical passageway therethrough coaxial with said flaring passageway and of substantially the same diameter as the height of said flaring passageway, means forming lateral discharge orifices connecting with said flaring passageway through which the projectile propelling gases may escape, the outer end of said nozzle member having diametrically opposite openings formed in the side walls thereof 45 through which said terminal member is slid able into assembled relation, and means for detachably connecting said nozzle and terminal members together in assembled relation including a pair of grooves formed in the flat walls of said nozzle member adjacent the outer end thereof and extending laterally thereacross at right angles to the axis of said flaring passageway, and a pair of complementary tongues carried by said terminal member and adapted for sliding engagement with said grooves.
